UNITED STATES PATENT OFFICE

BRUNO ROSENBAUM AND OTTO POHLE, OF BERLIN, GERMANY, ASSIGNORS TO THE FIRM DR. ERICH F. HUTH G. M. B. H., OF BERLIN, GERMANY

COMMUNICATION SYSTEM

Application filed November 23, 1923, Serial No. 676,571, and in Germany September 20, 1922.

Various methods have been employed hitherto for transmitting signals by means of electrical oscillations for use in telegraphy or telephony. For this purpose it has been 5 customary to install in the various stations transmitters for calling and transmitters for conveying telegraph signals or telephone messages. For the same purpose receivers of the call signal and receivers of signal message 10 were also provided at these stations. There have been also in existence combined transmitting and receiving apparatus such that when switched in on a certain circuit, they were open to a call signal and by a change 15 in switching re-arranged for message signalling. The same applied to the receivers. In the latter case, however, it has been usual that the receiver when switched over to receive the calling signal, required less sensitivity than when connected for receiving telegraph or telephone messages.

This invention relates to a communicating system which is supplied with at least one call receiver in addition to a signal receiver, or 20 a combined receiver in the way described.

Consider first the condition of using a train of oscillations corresponding to one single wire between two or more stations, and consider further that such an oscillation is sent 25 along one single wire or one single assembly 30 of wires joining these stations. This invention has for its purpose such an arrangement that all the stations connected to this single wire will know immediately that a call is being made, further, that an optical signal will 35 appear showing that the line is busy and preventing the operators of such stations from making any call themselves on the same wire (and on the same signal oscillation).

40 Another object of this invention is that when a conversation on a train of oscillations is carried on between two stations, the other stations not engaged in the conversation are prevented from using the same wire.

45 This is accomplished by having an optical signal appear which indicates that the line is busy, so that the same train of oscillations should not be used by the other stations for the transmission of signals or for disturbing calling signals, or for carrying on conver-

sations. It is evident of course that the employment of the same oscillation by a station not engaged in the conversation, would disturb considerably the two stations using this oscillation.

55 Another object of this invention is to take into account circumstances where it may be difficult to carry out strictly the above scheme. Frequently it is necessary to break into a conversation with an urgent message (Government calls). It may also be necessary to introduce emergency calls (as in wireless signalling between ships). For these emergency cases the invention provides a possibility for giving an emergency call signal, and for distinguishing this, although still using the same oscillation.

60 In order to explain the above assumed case of connecting several stations with a single oscillation the following may be stated. It is immaterial whether an oscillation is radiated or directed along the wires, this signal oscillation will always be able to maintain connection within its reach between two or more stations. If station A wishes to connect with 65 a certain station B and for this purpose uses an oscillation of a certain frequency, this means that at the moment of the generation of the oscillations in the transmitter of the station A, an equivalent of wires is being laid, or of connecting channels established, between station A and all other stations whose 70 calling receivers are tuned to the same oscillation and are within the reach of the signal. The equivalent operation is therefore as if 75 wires were strung from station A to all stations tuned to the same frequency within the reach of this signal, and lasting as long as the transmitter works on this frequency. As 80 soon as a selected station B enters into connection with station A, the other stations within reach must not simultaneously use the same oscillation either for receiving or for transmitting. The invention therefore provides 85 means which insure the exclusive use of this oscillation for connection between the two stations. This invention therefore provides, as it were, a wire between these two stations and prevents the use of the same wire by other stations. If, however, the station A wishes 90

95

100

to make the same connection to several stations, B, C, D, and so on, then the invention provides means to extend the same wire to all of these stations in the manner of a communication oscillation. Lastly, this invention provides a means to introduce into such normal connection an urgent or emergency signal on the same wire, (meaning the same oscillation), at least for the purpose of calling.

The first method of this invention is that the frequency of the call and traffic signal are identical. This still allows the use of selective reception and selective transmission at the receiving and transmitting stations respectively. The transmitting apparatus however is made so that the nature of the call signal may be changed in different manners. Thus, the call signals may vary in the length of time, for instance, each station may have a different length of time, one of them may have an uninterrupted signal of two seconds, the next an uninterrupted signal of three seconds and so on. Another form would have a call signal which may consist of two or more signal impulses of the same length of time or of different lengths of time, thus giving it first an uninterrupted signal of one second, then an interval of one second, then another signal of one second, while for another station there may be three such signals. Furthermore, the length of time of the uninterrupted signals as above may be varied, or the number of signals, or the length of time of each signal among a number may be varied, or the length of intervals among the interrupted call signals may be varied. It is evident that by this means a large variety of different call signals may be arranged, always using the same call frequency.

This is referred to as a horizontal arrangement, that is, all the call signals are on the same frequency level. It is further possible to have a vertical arrangement, that is, with the signals at different frequency levels. For instance, the station B called on a frequency of 100,000 will switch over automatically after receiving this first signal, to another wave, say 90,000 frequency. The station C having received the same call signal of 100,000 will change over to a frequency of 110,000. The third station, D, may switch over automatically to a frequency of 80,000, and so on. The calling station will now give the second signal on a new frequency, of, say, 90,000, and thereby definitely call station B. Thus, station B may have an arrangement for automatically ringing a bell when the second signal arrives. Simultaneously, an optical signal that this line is busy will appear on this and other stations. The bell will continue to ring until the operator will lift the receiver, or in other way respond to the call.

It is also possible to combine this horizontal arrangement with such vertical arrangement. This may be done as follows: A certain group

of receiving stations would be tuned to the same signalling frequency. The calling station will give a signal on this frequency, either one uninterrupted signal or a combination signal as described above. This would permit a differentiation among further groups of stations, one, for instance, responsive to a call of one second in length, another group to a call of two seconds in length, and so on. Whether such a preliminary selection is made or not, it is possible to have a further selection by means of an arrangement which will automatically switch over the receiving sets to another frequency.

At the other stations, at which the second signal did not arrive, the receiver may automatically return to its original position, after having waited during a specially assigned interval, and not receiving the second signal. This waiting may be secured by mechanical means, the call receiver being retained in a certain position during a period of time by means of a clockwork operating a release mechanism. This waiting terminates if the second signal does not arrive. It is evident now that at stations C, D, and so on, the call receiver will automatically be switched over to its original receiving frequency, after having waited without any results for a second signal. As the messages between stations A and B go on at the original frequency of 100,000, the following will take place:

The call receivers at all other stations are continually affected by this frequency and will switch over after a certain period of time (say two seconds) to the second frequency, say 110,000, 90,000, and so on. Since this second frequency will not arrive, they will return again after the expiration of the waiting time to the frequency of 100,000, and the same operation begins again, as long as the conversation on 100,000 frequency continues. The call receivers may be constructed in such a way that as soon as the first signal of 100,000 frequency arrives, an optical signal "busy" will show up and will be maintained during the whole of the waiting time, and continue to be held on "busy" as long as the conversation goes on at another station. It may disappear only for a fraction of a second at the end of the waiting period, when the call receiver is returning again to its original frequency. This will give an instantaneous blinking of the optical signal "busy" and will under no circumstances permit the operator of stations C, D, etc., to operate his instrument and thereby disturb the conversation going on between stations A and B.

It may be practical in cases of heavy service, using a number of stations, as for instance, for carrier wave transmission on high tension lines in industrial districts, with hundreds of stations connected, to combine a vertical arrangement with a horizontal arrangement. In such a case the first impulse

of 100,000 cycles will be given different lengths of time (one, two, three seconds, etc.). These signals of the same or different lengths will follow each other in various numbers, 5 making up a combination call which it is again possible to vary by different intervals. When in this way a group of ten stations is switched over from a signalling frequency of 100,000 to a signalling frequency of 90,000, 10 another combination signal is transmitted on this 90,000 frequency, picking out definitely the station called. If this, however, would imply too much complication, it is possible for a still smaller group of stations to 15 change over to a third frequency of, say, 60,000 cycles. If, for instance, three stations are changed over to a frequency of 60,000, it is only necessary to supply selective signals of one, two or three seconds on this 60,000 20 frequency, picking out the station desired. The traffic may be again carried on at 100,000 cycles. In this case it is necessary to give all the other stations a sufficiently long waiting period so that the return to the original 25 position does not occur until the call is completed. This would insure that the "busy" light signal will not disappear.

It is evident, however, that such an arrangement would allow only very few conversations, as a large number of stations are connected together with a single message frequency, for instance, 100,000. There are several ways of avoiding this difficulty. Thus, 30 several message frequencies may be used. 35 For instance, in the above vertical arrangement, supposing a call ends on a 60,000 frequency, the messages may now be conveyed on the same frequency to station A, but the call receiver of the other two stations, B 40 and C, having the same frequency signal of 60,000, would return again to their original positions. If it happens that one of these other stations, say station B, is again called on a frequency of 60,000, this call receiver 45 will perform its duty, but when going on the 60,000 frequency, a "busy" signal will appear. The ringing bell, however, will not operate, as the receiver of this station B would be arranged for a final signal of a 50 certain length of time, and since station A continues the conversation on a frequency of 60,000, this conversation or messages would blot out the final calling signal of station B and not permit the bell to ring on this station. 55 The optical sign "busy" will continue to appear at this and other stations. Nothing is to prevent the interfering station from listening in on this frequency of 60,000. If, on the other hand, the three stations with 60 the final calling signal of 60,000 frequency are assigned different message frequencies, such as 65,000, 61,000, and 58,000, then this listening would be impossible.

This invention is not limited to the messages carried on one frequency in both di-

rections, but may also be extended to messages between two stations on two different frequencies.

With the above horizontal arrangement, after the calling has been completed, all the 70 call receivers may return to their original position, except that an optical signal "busy" will appear on those stations which have the same call frequency as the message frequency of the station in operation. This is signified 75 by a blinking signal. Directions may be given to the operators to abstain from the use of apparatus under such conditions, or else an automatic lock may be introduced, consisting of a relay which is operated by the call receiver in the same way as the optical signal "busy" and which would prevent the lifting of the receiver by the operator or operating any other switch on the 80 receivers of the stations not in operation. Even more intricate arrangements may be provided to put out of action the device automatically when an urgent, or emergency, call arrives.

The emergency call may be introduced as 90 follows: A call receiver may have a second position corresponding to the waves otherwise not employed, for instance, by using two circuits of different frequencies, one corresponding in the previous instance to, say, 95 a frequency of 100,000, and another to a frequency of 130,000. This latter frequency will then serve for the emergency calls, which would be identical for all stations. It is possible to use the same receiving and amplifying valves by insertion of selective circuits suitable for the emergency frequency. This would allow the emergency frequency always to be heard, whether the particular receiving station is operating, or only shows 100 an optical signal "busy", or is idle. In the 105 first two cases, a ringing of a bell, which is impossible under ordinary circumstances, would attract the operator, in the case of emergency. The emergency call is thus transmitted at a frequency of 130,000. The conversation formerly conducted will be therefore interrupted and all of the stations must follow a rule and switch over to the emergency signal, which may be 130,000 frequency, as above, 110 or any other frequency.

A further arrangement for emergency signals arises where the emergency signals are not intended to be conveyed to all of the stations, but only to a certain group. It is 120 even easier in this case to give the emergency call properly. It is only necessary for all of the receivers of the stations in this group to return to their original position of readiness for receiving as soon as a call has been completed. It is then only necessary to give a common combination of signals for this group, which may end, say, as at 60,000 frequency as above. When, however, this final frequency is reached, the receivers called may 125 130

switch in a second circuit or an additional coil tuned to a frequency of 130,000, never used under any other circumstances except for emergency. If the emergency call is passing at this time, it will operate the calling bell and switch out all the other messages. The operator of a station which may be carrying on a conversation at this instant, would immediately inform his party that he is to receive an emergency call, and would then interrupt the conversation.

The same expedients can be used for transmission of telegraph or telephone signals, it is only necessary to provide a distinction between the length of time between telegraph signals and call signals.

It may be mentioned also that it is often possible to use medium or low frequencies for signalling, while high frequency is used for messages. A further modification is possible by assigning to each group a definite initial call frequency, say five stations at 5,000 frequency, five stations at 10,000 frequency, etc.

In addition, it is possible that the call signal would indicate the type of transmission to be used, for instance, whether it is telegraphy, telephony, high or low frequency, multiple telephony or telegraphy, etc. An arrangement of phantom circuits may be called for which would reduce the number of channels required.

It will be evident to those skilled in the art that it will be necessary to make the conductors suitable to the purpose. For instance, for carrier wave operation, a group of lines may be used or a single line. Since the messages may be conveyed either at one frequency (horizontal arrangement) or with a number of frequencies (vertical arrangement), it is possible to pick out the system of lines which is most suitable for a certain frequency of transmission. For instance, it may be possible in transmitting on certain frequencies to tune a total length of a line or a section of it by addition of coils, capacities, or both, when such tuning means would act as choke coils for all other frequencies. Interference may be prevented by properly protecting a group of wires by transposition. If, however, several frequencies are used, as in the vertical arrangement, it is advisable to arrange the tuning over a wider frequency range, by giving the total group of wires a group tuning for each of these frequencies or by selecting a single tuning with a flat resonance characteristic.

If a group of wires is used for transmitting single frequency or a group of frequencies, it is advisable to reduce the attenuation of this group or this signal wire by suitable tuning, and preventing interference by suitable counter-tuning.

In another modification, it is possible to arrange the receivers in cascade so that the

first receiver called after completing the call puts to work a second one, and so on.

Having described the object of our invention, we will now give an illustration of the manner in which it is carried out.

Figure 1 is a diagrammatic representation of the calling arrangement on the transmitter.

Figure 2 illustrates the operation of this calling transmitter.

Figure 3 is a diagrammatic representation of the receiving circuit.

Referring to the drawings, we have shown in Figure 1 a panel of insulating material 1, of a circular form with shoulders 3 and 4. Shoulder 3 controls a contact lever 5, shoulder 4 a contact lever 6. The contact 5 when touching the opposite contact 7, inserts a relay 18, while the contact 6 switches in or out by means of the opposite contact 8, a coil or a section of a coil 25, or capacity, or both, belonging to the antenna tuning circuit, thus throwing the transmitter considerably out of resonance with the signal frequency. In Figure 1 the transmitter is at rest, that is, switched off and the antenna circuit tuned, as contacts 5 and 7 are open and contacts 6 and 8 closed and as thus coil 25 is short-circuited. On the panel 1 there is a pin of insulating material 9 and a fixed contact pin 10, the latter being connected through coil 25 to the contact 6. On the shaft 2 there is fastened a contact arm 11. In the rest position as shown, the contact arm 11 touches the stop 12, while on the other end it touches the pin 9.

A clockwork not shown in the diagram tends to move the panel 1 in the direction of the arrow 14. A fairly weak spring which is not shown in the diagram tends to turn the contact lever 11 on the shaft 2 in the direction of arrow 15. A dial, not shown in the diagram, provided with stopping points and a working knob, carries a pin 16 by means of which the lever 11 may be turned in the direction opposite the clockwork, that is, in the direction of arrow 17, through an angle which may be predetermined in such a manner that the panel 1 would return to the position shown, in a fixed length of time. This adjusting knob attached to the dial is operated by hand, into a position corresponding to the call of a certain station, that is, to a certain frequency or a certain length of time. When this adjusting knob is brought into this position, it will simply cause contact 5 to touch contact 7 and operate the transmitter, which will then transmit continuously the frequency out of tune, since the contact arm 11 is touching pin 9 and the contacts 6 and 8 are open. When the working knob is released, the panel starts immediately returning to its original position, carrying with it pin 16 and thereby affecting the movement of the remaining parts.

The panel 1 controlled by the clockwork will return at uniform speed in the direction

- of arrow 14 to its original position. Simultaneously the contact arm 11 which may have had the first position I, indicated by dotted line, is driven by the spring in the direction of arrow 15 faster than the panel 1, and will assume a position II, touching contact 10 and eliminating the de-tuning of the transmitter by short-circuiting coil 25. In this position panel 1 and contact arm 11 continue to move 10 on in the direction of arrow 14 until contact arm 11 arrives again at the fixed stop 12, and is held there. Panel 1 keeps on moving in the direction of arrow 14, thereby disconnecting arm 11 from the contact pin 10, and 15 again bringing the transmitter out of tune. Eventually pin 9 will again touch the contact arm 11, and will bring the panel 1 to rest, at the same time switching off the transmitter and eliminating the out-of-tune wave 20 of the transmitter by making contact 6 touch contact 8. 26 represents the antenna, 28 is a high frequency generator coupled with the antenna circuit by means of an inductive coupling arrangement 27. 29 represents the 25 ground connection of the antenna 26. Referring to Fig. 2, at point *a* of the horizontal axis which represents the time, the working knob has reached the position where the mechanism will later transmit a five second, 30 100,000 frequency signal. At point *b* this working knob is released and this 100,000 frequency signal is transmitted until point *c* is reached, after a lapse of five seconds. At this point contact arm 11 has arrived at stop 35 12, and the transmitter will go on, but on a different frequency, that is, of 90,000. This frequency is transmitted until point *d*, when panel 1 has returned to its rest position and the transmitter is again switched off, and the 40 call is finished. After this, the contact 18 is closed, for instance, by lifting off of the receiver at the calling station, indicated at point received, and immediately the 100,000 frequency is continually transmitted and 45 used for telephonic or telegraphic communication.
- It is of course possible instead of throwing the transmitter out of tune, to disconnect it entirely. Figure 3, which illustrates a receiving system, shows at terminals 20 and 24, connections with any suitable source of current; the terminal 24 may be the positive terminal and terminal 20 the negative terminal. Between terminals 22 and 23 there is a bell 30, 50 while between terminals 24 and 25 there is a standard telephone instrument. This telephone instrument has a contact 31 which is opened as soon as the receiver is taken off the hook. The switches 32 are the usual type 55 three-point switches, connected in one position to bell with the receiver and in the other position to the call receiver, while in the third position it is switched off. The position connecting the call receiver may be also 60 used for receiving emergency signals.

As soon as a call signal is received (for instance, a 100,000 frequency) a lever 33 of insulating material is moved by clockwork with a magnet 36 in the direction of arrow 34. This is achieved by having a galvanometer 70 type relay responsive to the signal and lifting by its electro-magnetic action the latch holding the clockwork. At the same time an optical sign "busy" (35) will appear and the magnet 36 is excited while the lever 33 is 75 moved in the direction of arrow 34. It is evident that for this purpose the terminal 37 of the magnet must be connected to the minus side of the current supply.

The rotating lever 33 and the contact arm 80 38 are connected with terminal 37. A second contact arm 39 is arranged to rotate around the pin 40 and is held in position by the spring 44. If after a certain length of time contact 38 touches contact 39, the 85 circuit is closed from terminal 37, via contacts 38 and 39, to the conductive pin 40, coil 42, and hence to positive terminal 24. The coil 42 is thereby energized and causes contact 43 to turn against the force of spring 90 44 in the direction of the arrow as shown around the pin 45. This contact 43 will then arrive on top of the double lever 47 which has in the meantime come down, rotating around pin 46, carried by arm 33. 95

Supposing it is this station that is being called and that it requires a signal impulse of five seconds' time. During such a time the process as described above will have taken place. The contacts 38 and 39 have touched and the bent part of 43 has turned over. The signal impulse has now ceased, the magnet 36 is switched off and the arm 33 tries to return by the action of a spring, which is not shown on the drawing, to its original position. Hence the bent part of 43, which is still touching the double lever 47, will tend to rotate it somewhat against the action of the spring 48, making this double lever 47 touch the arm 49. This closes a circuit from terminal 37 via contact 49, double lever 47, wire 46', coil 47', wire 48', terminal 25, and hence to the positive terminal of the current supply. This will close the automatic contact 50 and the terminal 37 is connected to the receiving current in spite of the fact that magnet 36 is disconnected. Also, the coil 47' has a second contact 51 which is closed, connecting terminal 22 and bell 30 in the circuit, and causing the bell to ring. If, however, 115 the receiver is lifted, the switch 31 is opened, disconnecting coils 42 and 47' and switching off the bell. The bent part of 43 is then removed by spring 44 from the double lever 47 and the arm 33 returns to its original position. 120

If a signal of shorter period of time reaches the apparatus, it is evident that the magnet 36 becomes disconnected before the bent part 43 catches the double lever 47, and therefore 130

the optical signal "busy" will disappear at once, as soon as the signal of, for instance, three seconds' time, is over. The arm 33 may then return without inserting the bell in the circuit.

5 If however, the signal is of a longer period of time, for instance, eight seconds, then the apparatus moves beyond the position in which levers 38 and 39 touch. Their ends will then 10 slip off one another and before the call signal ceases. Hence there will be no current between those two contacts. The bent part 43 which after five seconds' period caught lever 47, is after five and one-half seconds again 15 taken away by the spring 44, since contacts 38 and 39 are no longer touching and the coil 42 is de-energized. After eight seconds the lever 33 may again return without hindrance into its original position. In this 20 latter case, in order to prevent the lever 33 from going too far down and causing the contacts 38 and 39 to hit heavily against each other, the clockwork may be switched off entirely after 5.7 seconds. This is done by 25 means of contact 52 on arm 33, which hits lever 54 and thereby neutralizes coil 53 (contact 52, lever 54, and coil 53 are illustrated by a separated circuit in this diagram). Coil 53, when de-energized, stops clockwork.

30 Having now particularly described and ascertained the nature of our said invention and in what manner the same is to be performed we declare that what we claim is:

1. A signalling system for a number of 35 stations on a common communication channel comprising a common signaling frequency, means to call all of the stations from any single station by said common frequency, means to select any one of the called stations 40 and transmit a message by said common frequency, and further means also operated by said common frequency at all of said stations for prohibiting the non-selected stations from effecting communication as long 45 as traffic with said selected station continues.

2. A signalling system for a number of 50 stations on a common communication channel comprising means to call all of the stations from any single station on a common frequency, means responsive to said frequency at all of said stations operated periodically as long as reception of said frequency continues, a selecting arrangement for each of 55 said stations for sending a continuous selecting signal wave on said frequency, the selecting signal being of longer or shorter duration corresponding to the station with which communication is to be effected, and means whereby signalling communication is established by cooperation of said selecting signal with said second means.

3. A signalling system for a number of 60 stations on a common communication channel comprising means to call all of the stations from any single station on a common fre-

quency, mechanical means responsive to said frequency at all of said stations operated periodically as long as reception of said frequency continues; and means in connection with said first means at each of said stations for sending a continuous selecting signal wave on said common frequency of shorter or longer duration allotted to each of said stations respectively, said selecting signal co-operating with said mechanical means for establishing signalling connection between the calling station and the selected station.

4. A signalling system for a number of stations on a common communication channel, comprising a transmitting and receiving apparatus at all of said stations, means to call all of the stations from any single station on a common frequency, a mechanical element at all of said stations adapted to carry out periodical movements as long as reception of said frequency continues, cooperating means for prohibiting communication of said stations, means in connection with said first means at each of said stations for sending a continuous selecting signal wave on said frequency of a shorter or longer duration allotted to each of said stations respectively, and means for establishing signalling connection between calling station and selected station by cooperation of said selecting signal with said mechanical element.

5. A signalling system in accordance with claim 4 according to which said mechanical element has the form of a lever provided with a contact movable relative thereto against the force of a spring, a further stationary contact also movable against the force of a spring and adapted to engage said first contact, whereby the relative position of said contacts is such that engagement takes place after a certain lapse of time corresponding to a distinct position of said lever in accordance with the respective duration of the selecting signal and means to disconnect said device and connect said apparatus to the signalling channel by the engagement of said contacts.

6. A signalling system in accordance with claim 4 in which said first means consists of a dial associated with a contacting device, means including a spring for setting said dial at a distinct position and releasing it to return to its zero position, and means associated with said contacting device for sending out a selecting signal of distinct duration corresponding to the station which it is desired to call.

7. The method of communication which consists in calling a number of stations by a train of oscillations of given frequency, selecting the desired station and then transmitting a desired signal on said frequency while at the same time keeping the remaining stations inactive by said same frequency.

8. The method of communication which consists in calling a number of stations on a
